Carl Scholz Inventor

John Boyle Jr
Attorney

UNITED STATES PATENT OFFICE.

CARL SCHOLZ, OF CHARLESTON, WEST VIRGINIA.

MINE CAR.

Application filed October 25, 1921. Serial No. 510,321.

To all whom it may concern:

Be it known that I, CARL SCHOLZ, a citizen of the United States, residing at Charleston, in the county of Kanawha and State of West Virginia, have invented certain new and useful Improvements in Mine Cars, of which the following is a specification.

My invention relates to mine cars and one of the objects of the invention is to provide a composite body construction, that is, one in which a portion is made of structural iron, while the remainder is made of wooden planking. The chief objection to all steel cars are their rigidity and liability to take a permanent set, if once bent out of shape. On the other hand, a wooden car is much more flexible, and will give to compensate for unevenness in the track, but deteriorates much more rapidly than a steel car. In a car of the composite construction, many of the desirable points of both wood and steel can be embodied.

Another object of the invention is the construction of an underframe comprising channel irons so arranged that the floor of the car is continuous and extends beyond the ends of the car body to serve as bumpers.

A further object of the invention is to provide a car having an increased capacity and at the same time keeping its height and center of gravity low.

With these general objects in view, the invention consists in certain novel and peculiar features of construction and combination of parts as hereinafter described and claimed; and in order that it may be fully understood reference is to be had to the accompanying drawings, in which similar reference characters indicate corresponding parts in all the views.

Fig. 1 is a plan view of the car;

Fig. 2 is an elevation and fragmentary section;

Fig. 3 is a section on the line 3—3 of Fig. 1, and

Fig. 4 is a detail view.

Referring to the drawings for a further disclosure of the invention, 1 is the floor of the car constructed of wooden planks running lengthwise thereof. The inside planks 2, 3 and 4 are extended beyond the ends of the car body to provide bumpers, the ends of which are cut to provide a curved surface, which is protected against wear by the metal armor plate 5. Reinforcing the

floor extensions are supplementary wooden pieces 5^a secured thereto.

Running transversely of the car at each end and supported on the floor are channel irons 6. Running longitudinally of each side of the car and secured to the under side of the bottom is a steel plate 7, which projects sidewise beyond the bottom to provide steps 8 on which rest the channel irons 9. The depth of the channel irons 9 is sufficiently greater than the depth of the channel iron 6 so that the upper surfaces are all in the same plane. Rigidly secured to the channel iron underframe, is a series of vertical angle irons 11, connected together at their upper ends by the horizontal angle irons 12, the corner angle irons at their lower ends being secured respectively to a transverse and longitudinal channel iron for holding the same in rigid relationship, as particularly shown in Fig. 4.

Supported by the channel irons 6 and 9 and rigidly secured to the angle irons 12 are the wooden side and end planks 13.

Secured to the bracing plate 7 are roller bearing journaled boxes 15^a for supporting the wheels 14 and axles 15. The floor of the car is cut away to provide openings 16 for the wheels, these openings being covered by hoods 17 secured to the inner side of the bottom of the car.

For bracing the car transversely, intermediate the ends, there are provided a series of angle irons 24 secured to the bottom; and at each end, there is a transverse plate 23. Brackets 18 are secured to the inner side of the car body for also bracing it.

The draft gear at the end of the car is covered by a housing 19 and comprises a draw bar 20, and an abutment 21, with a spring 22 interposed therebetween to resiliently take up the shocks incident to starting the train of cars.

I have referred herein to the underframe construction as comprising channel irons, but any of the other well known equivalent structural shapes could be substituted therefor without departing from the spirit of the invention.

From the above description it will be apparent that I have produced a device of the character described, which possesses all the features enumerated as desirable, and while

I have illustrated and described the preferred form of the invention, it will be understood that I reserve the right to all changes properly falling within the scope 5 and spirit of the appended claims.

Therefore what I claim as new and desire to secure by Letters Patent is:

1. A mine car body having an underframe construction comprising horizontal channel irons, a floor interposed therebetween, the said irons extending a substantial distance above the level of the floor, the flat side of the channels being on the inside 10 of the body.
15. 2. A mine car body having an underframe construction comprising horizontal channel irons, a wooden floor interposed therebetween, the said irons extending a substantial distance above the level of the floor, the flat side of the channels being on the inside 20 of the body, and a wooden superstructure supported on the channel irons and in the same plane therewith.
25. 3. A mine car body having an underframe construction comprising structural iron members, a floor interposed therebetween, vertical irons secured to the said members and a wooden superstructure supported on the said members in the same plane there- 30 with and secured to the outer side of the said last named irons.
35. 4. A mine car body having an underframe construction comprising side structural iron members, and transverse structural iron members which connect the ends of the side members, a wooden floor interposed between the side members and extending beyond the transverse members to provide end bumpers, the said transverse members resting on 40 the floor.
45. 5. A mine car body having an underframe construction of structural iron members, a wooden floor interposed between the said members and reinforcing plates extending longitudinally of the bottom along the sides.
50. 6. A mine car body having an underframe construction of structural iron members, a wooden floor interposed between the said members and reinforcing plates extending longitudinally of the bottom along the sides and axle boxes secured to the said plates.
55. 7. A mine car body having an underframe construction comprising side and end channel irons, the flat side of the channels being on the inside of the body, vertical angle irons secured to the said channel irons for supporting the sides of the body, the corner angle irons being secured to the flat sides of a side and end channel respectively for holding the same in fixed relationship.
60. 8. A mine car body having an underframe

construction comprising side and end members, the end members being of less depth than the side members, the upper surface of the side and end members being in the same 65 plane.

9. A mine car body having an underframe construction of channel irons, the flat side of the channels being on the inside of the body, vertical irons secured to the said channels, horizontal angle irons connecting the upper ends of the vertical irons, and wooden sides interposed between the flange of the channel irons and the flange of the angle irons. 70

10. A mine car body having an underframe construction of structural iron members, a wooden floor interposed between the said members and reinforcing plates extending longitudinally of the bottom along 80 the sides, the said plates extending beyond the sides to provide a step for supporting the side members.

11. A mine car body having an underframe construction comprising side and end 85 members, a floor interposed therebetween, the end members being of less depth than the side members, both of said members extending a substantial distance above the level of the floor and having their upper surfaces 90 in the same plane.

12. A mine car body having an underframe construction comprising side and end structural iron members, a wooden floor interposed therebetween, the end members being of less depth than the side members, both of said members extending a substantial distance above the level of the floor and having their upper surfaces in the same 95 plane, and a wooden superstructure supported by the said members. 100

13. A mine car body having a wooden floor, an underframe construction comprising end irons resting on the floor and side irons connected to the end irons. 105

14. A mine car body having an underframe construction of structural iron members, a wooden floor interposed between the said members, reinforcing plates extending longitudinally of the bottom and along the 110 sides, portions of the floor between the said plates extending beyond the end of the body to provide a buffer.

15. A mine car body having an underframe construction comprising side and end 115 members, a wooden floor interposed between the side members, the end members being of less depth than the side members, the difference in depth being equal to the thickness of the floor.

In testimony whereof I affix my signature.
CARL SCHOLZ.
